PORTABLE WELDING SCREEN

Harold D. Hampton, United States Army,
Aberdeen Proving Ground, Md.

Application October 17, 1941, Serial No. 415,498

8 Claims. (Cl. 160—355)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a screen for use in conjunction with welding operations.

The purpose of the invention is to provide a light, rugged, collapsible screen for use in the field by military maintenance organizations to protect the vision of personnel working in the vicinity of places where welding is in progress.

The specific nature of the invention as well as other objects and advantages thereof will clearly appear from a description of a preferred embodiment as shown in the accompanying drawings in which:

Fig. 1 is a front elevational view showing the screen set up in a shielding position.

Fig. 2 is an enlarged view, partly in section, of one of the spikes for erecting the screen on soft ground.

Fig. 3 is an enlarged, fragmentary elevational view of an intermediate upright or staff.

Fig. 4 is a plan view, partly in section, illustrating the manner in which a link is coupled to an upright.

Fig. 5 is an enlarged elevational view of one of the intermediate staves with its connecting links in a collapsed or folded position.

Fig. 6 is a front elevational view of the top portion of an intermediate upright.

Fig. 7 is a view in side elevation showing the manner of attaching the flexible wall to an upright.

Fig. 8 is a front elevational view of the top of the right hand end upright of Fig. 1.

Fig. 9 is a plan view showing a connecting link coupling two of the uprights together.

Fig. 10 is a view in front elevation with parts in section illustrating the ends of a pair of folded connecting links confined in a retaining sleeve, and

Fig. 11 is an enlarged elevational view with parts in section showing the manner in which the fabric wall is secured to an upright.

Referring to Fig. 1, the screen comprises a pair of end uprights or staves 10, spaced intermediate staves 11, and folding interconnecting links 12 which provide a substantially rectangular frame. A treated fabric wall 13 preferably made of canvas is stretched and secured to the frame. The staves are fitted with spikes 14 which are adapted to permit easy insertion in soft ground. The lower portion of the fabric 55

wall 13 has a plurality of spaced slits or notches 15 so as to provide a series of flaps 16. This allows the bottom of the screen to conform to uneven ground and makes a more effective light shield. The links 12 are arranged to be disengagable from sockets in certain of the uprights and folded parallel to the staves whereupon the screen components may be rolled up in the fabric wall into a compact bundle for transport purposes. A pair of straps 17 and buckles 18 are secured to the fabric at the right hand post and serve to hold the bundle together.

The staves 10 and 11 are made of a light durable material and are preferably a light steel tubing flattened at the top ends 19 and provided with holes 20 for attachment of guy ropes (Figs. 1, 5, and 7). A spike 14 (Fig. 2) is fitted in the lower tubular end of each staff and is secured by a rivet 21. Each staff except the one shown on the extreme right of Fig. 1 has a pair of lugs 22, one brazed or welded near the top and the other about six inches from the bottom. Pivotally mounted on each of these lugs is a connecting link 12 having its free end bent at a right angle so as to form a hook 23, see Figs. 5 and 6. Each link 12 is preferably a tubular member and receives a flat steel tongue 24 which is welded thereto near one end and is pivoted to the lug 22 by a pin 25 at the opposite end, see also Fig. 4.

The intermediate staves 11 are provided with tubular sockets 26 which are welded thereto substantially diametrically opposite the lugs 22. These sockets are slightly larger than the diameter of the interconnecting links 12 and are adapted to receive the hook portions 23 as shown in Figs. 1 and 6.

The staff 10 on the right hand end has similar sockets 27 conditioned to retain interconnecting links in hooked engagement. The upper ends of these two sockets have a pair of ears 28 which are arranged to engage the horizontal end portions 29 of the links 12, see Figs. 1, 8, and 9. These sockets are conveniently formed by slotting their upper ends and flaring them as illustrated in Fig. 9. The ears 28 prevent the right hand staff 10 from rotating when the links are locked therein in the assembled position and adds to the rigidity of the unit.

The flexible wall or cover 13 is folded about the end staves 10 and sewed at 30 so as to envelope them in pockets 31. The four corners of the cover, as well as a plurality of intermediate points, are provided with brass grommets 32 which are affixed in apertures 33, see Figs. 7 and

11. Holes 34 are drilled adjacent the ends of the staves 10 and 11 and receive bolts 35 which are also threaded through the grommets in the cover. A nut 36 locks this assembly to the posts. A plurality of spaced canvas bands or sleeves 37 are wrapped over the intermediate staves 11 as shown in Figs. 1 and 6 and sewed to the fabric wall 13. These act to secure the wall to the framework at several points.

Slidable fabric retaining sleeves 38 surround the top interconnecting links 12 as shown in Fig. 1. Each sleeve is a folded member sewed along the bottom edges 39 and its passage has a restricted portion 40 formed by stitching in a corner 41.

The fabric wall 13 is preferably coated on one side with an ultraviolet ray protective paint to provide a more effective light shield.

The operation of the device is as follows. To set up the screen the hooks 23 of the folding links 12 are inserted in the tubular sockets 26 on the staff to the immediate right. Likewise a pair of links 12 are depressed in the sockets 27 on the right hand staff 10. This completes the assembly of the frame structure and causes it to become rigid. Simultaneously the canvas wall 13 is stretched taut and imparts additional rigidity because of the cross bracing effect of the fabric panels. The staves 10 and 11 are depressed so as to force the spikes 14 into the earth. By arranging the staves in other than a straight line, stability is imparted to the erected screen. Guy ropes are unnecessary except in unusually windy weather.

To collapse the screen the hooks are removed from their respective sockets and folded parallel to their supporting staves. The retaining sleeves 38 on the upper connecting links are slid downward so as to envelope the pair of hooks of the folded links of each staff as shown in Figs. 5 and 10. The stitched shoulder 41 engages the hook 23 of the lower link and prevents the sleeve from sliding downward out of a confining position. As a result the links are retained parallel to the staves. The screen is then rolled into a bundle and the straps 17 are employed to secure it in a compact cylindrical roll.

It is evident from the above description of the invention that there is provided a welding screen which is light, sturdy, simple in construction, easy to erect, can be quickly collapsed into a compact bundle for transport, and does not require the use of tools for assembling or dismantling operations.

I claim:

1. A portable screen for welding operations comprising, a plurality of spaced vertical uprights having pointed lower ends, spaced collapsible means interconnecting said uprights in series relationship, said means providing a sectionalized frame of rigid sections when assembled, adjacent sections being angularly displaceable with relation to each other, a wall of flexible material over said frame and secured to each of said uprights, an ultraviolet absorbing coating on said wall, and a flap at the lower end of said wall.

2. A portable screen adapted to be collapsed into a roll comprising when assembled, a series of spaced vertical staves, spaced folding links pivoted to all but one of said staves, hooks on the free ends of said links, socket members on all but one of said staves, said members adapted to detachably receive and confine said hooks on said links thereby providing a sectionalized frame of

rigid sections, and a flexible wall over said frame and secured to each of said uprights.

3. A portable welding screen adapted to be collapsed into a roll comprising when assembled, 5 a series of spaced vertical staves, spaced folding links pivoted to all but one of said staves, hooks on the free ends of said links, socket members on all but one of said staves, said members adapted to detachably receive and confine said hooks on said links thereby providing a sectionalized frame of rigid sections, a wall of flexible material over said frame and secured to each of said staves, a loose flap on the lower end of said wall, and an ultraviolet absorbing coating on said wall and 10 said flap.

4. A portable welding screen adapted to be collapsed into a roll comprising when assembled, a series of spaced vertical staves having pointed lower ends, spaced folding links pivoted to all but 20 one of said staves, hooks on the free ends of said links, socket members on all but one of said staves, said members adapted to detachably receive and confine said hooks on said links thereby providing a sectionalized frame of rigid sections, 25 a wall of flexible material over said frame and secured to each of said uprights, a flap on the lower end of said wall, an ultraviolet absorbing coating on said wall and said flap, and a strap member on one end of said wall for binding 30 said screen when collapsed.

5. A portable welding screen adapted to be collapsed into a roll comprising when assembled, a series of spaced vertical staves, spaced folding links pivoted about a horizontal axis to all but 35 one of said staves, vertically extending hooks on the free ends of said links, vertical socket members on all but one of said staves, said members adapted to detachably receive and confine said hooks on said links thereby providing a sectionalized frame of rigid sections having rotation 40 between sections about a vertical axis, a wall of flexible material over said frame and secured to each of said uprights, a flap on the lower end of said wall, and an ultraviolet absorbing coating on said wall and said flap.

6. A portable welding screen adapted to be collapsed into a roll comprising when assembled, 50 a series of spaced vertical uprights, pairs of spaced elongated hooks pivoted about a horizontal axis to all but an end upright, the pivots of said hooks being positioned adjacent the upper and lower ends of said uprights, spaced vertical socket members on all but the other end upright, said members adapted to detachably and pivotally receive and confine the free ends of said hooks thereby providing a sectionalized frame of rigid sections, said frame sections being angularly displaceable about the pivotal connection, a fabric wall over said frame and secured to each 55 of said uprights near the upper and lower ends, a vertically split flap at the lower end of said wall, and an ultraviolet absorbing coating on said wall and said flap.

7. A portable welding screen adapted to be collapsed into a roll comprising a series of spaced vertical staves, pairs of spaced folding links pivoted to all but one of said staves, hooks on the free ends of said links, a sleeve slidable on one of each pair of the folding links for confining the free ends of a pair of links when folded for 70 transport, each of said sleeves having a reduced passage for positioning the sleeve about the hook portions of the folded links, socket members on all but one of the staves, said members adapted to detachably receive and confine said hooks on

said links thereby providing when assembled a sectionalized frame of rigid sections, a wall of flexible material over said frame and secured to each of said staves, a loose flap on the lower end of said wall, and an ultraviolet coating on said wall and said flap.

8. In a collapsible screen, an upright, folding links pivoted adjacent the ends of said upright,

hooks on the free ends of said links, a fabric sleeve on one of said links, said sleeve having a reduced passage for the shank portion of said link and an enlarged communicating passage for receiving the hook portions of both of said links when folded parallel to the upright.

HAROLD D. HAMPTON.
